UNITED STATES PATENT OFFICE.

HERBERT S. MILLS, OF OAK PARK, ILLINOIS, ASSIGNOR TO MILLS NOVELTY COMPANY, OF CHICAGO, ILLINOIS, A CORPORATION OF ILLINOIS.

TREMOLO DEVICE FOR VIOL MACHINES.

Application filed March 29, 1926. Serial No. 98,219.

This invention relates particularly to improvements in tremolo devices for use in connection with stringed instruments of the viol class, such as machines of the character 5 described in Sandell Patent No. 855,021, of May 28, 1907.

The primary object is to provide an improved and simplified mechanism employing pulsating means for vibrating the tensioning 10 levers attached to the strings of a violin, for example—

The invention is illustrated in its preferred embodiment shown in the accompanying drawings, in which—

15 Figure 1 represents a broken vertical elevational view, partly in section, and pumping mechanism employed for delivering air pulsations; and

20 Fig. 2, a broken elevational view illustrating pulsating devices complementary to the mechanism shown in Fig. 1 and serving to impart vibrations to the tensioning levers illustrated.

25 In the construction illustrated, A designates the neck-portion of a musical instrument of the viol class which is provided with strings 1. The front end-portions of the strings 1 are connected with tensioning levers 2, 3, 4 and 5 which are pivotally supported at the point 6. The front end-portions of the strings 1 pass about grooved segments 7 with which the levers are provided and the strings are secured by tightening 30 means 8 mounted on the levers. Each lever 35 may be equipped with a weight 9 (one shown) for the normal tensioning of the lever. Any other desired tensioning means, as for example spring tensioning means, may be employed.

40 For tremolo purposes, the tensioning levers are adapted to be vibrated about the pivot point 6 by means of pistons 2^a, 3^a, 4^a and 5^a which are joined to the outer ends of the levers by suitable connecting rods, the 45 pistons working freely in cylinders 2^b, 3^b, 4^b, and 5^b, which preferably are pneumatic cylinders. The cylinders are shown mounted on a base 10. They are served by tubes 2^c, 3^c, 4^c, and 5^c regulated by valves 2^d, 3^d, 4^d, 50 and 5^d. The valves may be mounted in a common valve casing 11 interposed in the course of the tubes.

The tubes mentioned lead from the upper and lower ends of the cylinders of double

acting pumps. The pump device, shown in 55 Fig. 1, is designated B. It comprises a pair of fixedly mounted cylinders 12 and 13, which are equipped with pistons 14 (one shown). It is not necessary that the pistons fit very closely within the cylinders. In fact, 60 some advantage may be gained by using a loose fit.

The pumps are actuated by means of an electrical motor B' whose shaft 15 projects at both ends of the motor. The shaft is 65 equipped at one end with a worm 16 which drives a worm-gear 17. At the other end, the shaft is equipped with a worm 18 which drives a worm-gear 19. The shafts of the worm-gears are equipped with cranks 20 70 which are connected by rods 21 with the piston rods 22.

The gear ratios at the two ends of the motor are shown as different from each other. That is, the worm-gear 17 is smaller 75 than the worm-gear 19, and thus the right hand pump which serves the pulsating devices connected with the higher toned strings, that is, the A and E strings, reciprocates more rapidly than does the left hand pump which serves the lower toned strings, that is, the D and G strings.

Current passes to the motor through a cable 23 which is served through a switch 24 from a rheostat 25. Thus, the speed of 85 the motor may be regulated. Switch 24 may be located at any desired point. It may, for example, be located on a console fitted with a key manual which serves to control the electrical circuits which operate the 90 fining devices and bow-depressing devices of the machine.

The operation will be readily understood from the description given. The motor B' is actuated at the desired speed and operates the pump mechanism B which serves to deliver air to, or cause air pulsations in, the cylinders 2^b—5^b. Thus, the pistons 2^a—5^a will be actuated. The delivery of air may be regulated by the valves 2^d—5^d, and thus the amplitude of movement of the pistons 2^a—5^a may be regulated as desired. Ordinarily, these pistons do not have the same amplitude of movement. That is, the movement is regulated to suit the requirements, it being noted that the heavier strings require greater variation in the tensioning than do the lighter strings in order to get

the best tremolo effect. The improved mechanism is adapted to accomplish the purpose in a simple and effective manner.

Any suitable method of controlling the motor switch may be employed.

The present invention is in the nature of an improvement upon, or species of, the invention described in Herbert S. Mills U. S. application Ser. No. 703,176, filed March 31, 10 1924.

The foregoing detailed description has been given for clearness of understanding only, and no unnecessary limitations should be considered therefrom, but the appended 15 claims should be construed as broadly as permissible in view of the prior art.

What I regard as new and desire to secure by Letters Patent is:

1. In combination with tensioning levers 20 of the strings of a musical instrument of the viol class, a pneumatic pulsating device connected with each lever, conduits serving said pulsating devices, valves controlling said conduits, and pumping mechanism connected with said conduits.

2. In combination with tensioning levers of the strings of a musical instrument of the viol class, a pneumatic pulsating device connected with each lever, conduits serving said

pulsating devices, valves controlling said 30 conduits, pumping mechanism connected with said conduits, an electric motor for actuating said pumping mechanism, and means for varying the speed of said motor.

3. In combination with the tensioning 35 levers of a musical instrument of the viol class, a series of pistons connected with said levers, cylinders telescopically receiving said pistons, conduits serving said cylinders, valves controlling said conduits, a pair of 40 double acting pumps serving said conduits, and an electric motor provided with a shaft having its opposite ends equipped with gear mechanism connected with the pistons of said pumps.

4. In combination with the tensioning 45 levers of a musical instrument of the viol class, a series of pistons connected with said levers, cylinders telescopically receiving said pistons, conduits serving said cylinders, 50 valves controlling said conduits, a pair of double acting pumps serving said conduits, and an electric motor provided with a shaft having its opposite ends equipped with gear mechanism connected with the pistons of 55 said pumps, the gear ratios at opposite ends of said shaft being different.

HERBERT S. MILLS.
